UNITED STATES PATENT OFFICE.

WILLIAM S. HOLDAWAY, OF LOS ANGELES, CALIFORNIA.

DISK BIT.

Application filed April 6, 1925. Serial No. 20,985.

This invention relates to rotary disk bits of the type employed in the rotary method of drilling oil wells.

This invention is directed to improvements in the type of rotary disk bits employing a plurality of disk cutters mounted upon a prong body, the prongs being generally referred to in the art as legs. The bits of this type have generally been found to be the most successful in the rotary method of drilling wells. Such disk bits, however, have two major defects which has to a large extent hindered their most universal adoption in the drilling of wells. The first of the difficulties referred to is the tendency of the drilling action to wear away the bottom end of the legs during drilling operations compelling such legs to be repeatedly built up and increasing the danger that the pins or bushings or the like employed to support the disk cutters thereon will drop out of the legs and be lodged in the well hole. The second difficulty referred to is the tendency of the legs of the prong of the body to break away from the body which with the present form of rotary drilling bits generally causes the entire disk bit to be thrown away.

An object of the present invention is to provide a disk bit constructed with a leg detachable from the body so that it may be made of different material than the remainder of the body, and thus materially strengthen without increasing greatly the total cost of the disk bit and also furnishing a disk bit which upon the destruction of its leg may have it replaced by a new leg and thus the entire bit saved from discard.

Another object of the present invention is to provide a disk bit with a mounting for the disk cutters which will permit the lower ends of the legs to be materially worn away without increasing the danger of the disk being removed from the bit.

Various further objects and advantages of the invention will be understood from a description of a preferred form of rotary disk bit embodying the invention, for which purpose reference is made to the accompanying drawings.

In the drawings:

Figure 1 is an elevation partially in vertical section.

Fig. 2 is an elevation at right angles to Figure 1 with the upper end of the bit broken away and a portion of one of the legs broken away.

Fig. 3 is a section on the line 3-3 of Fig. 1.

Fig. 4 is a section on the line 4-4 of Fig. 1, and

Fig. 5 is a fragmentary view of the lower end of the body of the bit with detachable legs removed therefrom.

Referring to the drawings, the disk bit there illustrated comprises a body 2 having an elongated shank 3 provided with an enlargement 4 near its upper end and terminated in a threaded pin 5 by which the disk bit can be attached to a rotary string and rotated during drilling operations.

The shank 3 of the body is made of elongated form in order that if through some accident the bit would become broken off from the string and lodged in the well hole it may be readily gripped by fishing tools and removed therefrom. The lower end of the body 2 terminates in two spaced extensions or legs 6 and 7 which serve to mount disk cutters 8 and 9 respectively. The spaced legs 6 and 7 are of duplicate construction and therefore it is necessary only to describe the construction of one, both of the legs being preferably made detachable from the body 2.

The legs are preferably shaped to off-set the disk cutters 8 and 9 mounted thereby in order to bring such disk cutters in advance of the drilling axis of the bit. It can be seen that upon pressing downward upon the drilling bit and rotating the same there will be a resulted stress applied upon the legs 6 and 7 in a direction angled from the longitudinal axis of the shank 2 of the body. In order to properly hold the legs 6 or 7 to the body, it is therefore preferred to provide contacting surfaces between the legs and shank 2 of the body angled to most properly receive this stress and insure the retaining of the legs thereto. For this purpose the lower end of the shank 2 is recessed at its opposed sides as indicated at 10 and 11, respectively, thus providing upthrust bearing faces 12 and 13, respectively, for engaging the ends of the legs 6 and 7, respectively to impose upon the legs 6 and 7, and thereby

the cutters 8 and 9, the desired vertical load or feeding pressure without requiring this load to be transmitted thereto through the means utilized for fastening the legs to the shank.

These recesses are shaped with flat faces 14 and 15, respectively, enlarged slightly

downwardly and provided with trough like recesses 16 and 17, respectively, angled relative to the axis of the shank in the direction which the resulting stress upon the legs 6 and 7, respectively, will be imposed. The side walls of such sub-recesses are thus so formed that they act as bearing surfaces disposed to directly resist the stress applied upon the legs 6 and 7. The ends of the legs 10 and 7 are provided with surfaces shaped to fit the recesses 10 and 11 upon opposed sides of the shank, thus each leg is provided with a diagonally extending tongue 18 for fitting in sub-recesses 16 or 17 which are 15 angled relative to the axis of the shank 2 of the body.

Various means may be employed for clamping such legs and body together.

In the form of the invention shown there 20 is employed two upper bolts 19 and 20 and two lower bolts 21 and 22 clamping the legs to the body in such manner that to themselves insure the legs being maintained rigid with the shank 2.

25 The usual form of mounting for the disk cutters on the legs is by passing a pin through an opening near the end of the legs and mounting the disk upon such pin either directly or upon bushings mounted thereon. 30 With such construction the wearing away of the lower end of the legs will permit the pins to drop out leaving the disk cutters in the bottom of the well from which they must be fished out or ground up. The mounting 35 herein provided eliminates largely this difficulty by providing inturned bosses 22^a and 23 upon the legs 6 and 7, respectively, over which bushings 24 and 25 may be placed and locked thereto by suitable means, such as 40 bolts 26 and 27, respectively, thus providing a mounting for the disk cutters.

With the form of rotary disk bit herein illustrated it is readily apparent that the legs 6 and 7 may be replaced as destroyed 45 without compelling the purchase of an entirely new bit. Moreover, the legs 6 and 7 may be made of the highest grade of material to strengthen the disk-bit at its weakest point without compelling the whole bit to be 50 made of such high grade material, thus providing increased strength in the bit with-

out material increase in the cost. It should be pointed out that a large part of the material of the bit is disposed within the shank 3 which must be large and long in 55 order that bits broken off in the well hole may readily be engaged by fishing tool. Hence the fact that the legs of the disk bit of this invention may be made of different material than the body is of great advantage 60 in reducing the cost of the bit.

While the embodiment of the invention herein described is well suited for accomplishing the purpose of this invention, various modifications may be made in the details of construction of arrangement of parts without departing from the principles of the invention. The invention is not therefore limited to such construction details, but includes all such modifications and changes 65 as come within the spirit of the appended 70 claims:

I claim:

1. A rotary disk bit comprising a body recessed at its lower end on opposed sides to 75 form upthrust bearing faces and bearing faces angularly disposed, legs shaped to fit such recesses and engage such bearing faces, there being a tongue and groove connection between the legs and body, means clamping 80 the legs to the shank, and disk cutters carried by and between the legs.

2. A rotary disk bit comprising the combination of a body recessed at its lower end on 85 opposed sides to form upthrust bearing faces and bearing faces angularly disposed, legs shaped to fit said recesses and engaged by said bearing faces, the legs having a tongue and groove engagement with the body, the tongue being angularly disposed, means for 90 clamping the legs to said body, the legs being provided with integral bearing trunnions at their lower ends, and disk cutters carried by said trunnions.

3. A replaceable leg for a disk bit comprising an integral trunnion on the lower part of the leg adapted to support a disk, the leg at its upper end having an angularly disposed tongue.

Signed at Los Angeles, California, this 30 100 day of March, 1925.

WILLIAM S. HOLDAWAY.
